UNITED STATES PATENT OFFICE.

THOMAS NATHAN RUSSELL, OF CHICAGO, ILLINOIS, ASSIGNOR, BY MESNE ASSIGNMENTS, TO CHICAGO-CLEVELAND CAR ROOFING COMPANY, OF CHICAGO, ILLINOIS, A CORPORATION OF DELAWARE.

CAR ROOF.

Application filed October 11, 1923. Serial No. 667,980.

This invention relates in general to improvements in freight car roofs and more particularly to improvements in the rigid, all-steel, self-sustaining type of roofs for such cars, and objects of the invention are the provision of a well balanced, all-steel, rigid roof which may be used without certain longitudinal frame members of the car, such as purlins and the usual ridge pole; the provision of roof sections which are comparatively simple to manufacture, and which may be assembled on the car frame, and easily riveted to the carlines, notwithstanding slight irregularities in the spacing of such carlines; the provision of roof construction in which the flanges of adjacent sheets fit tightly over the carlines and are rigidly secured thereto, and engage said carlines so as to be water tight without requiring joint caps or other waterproofing means; and the novel arrangement of the various parts of said roof members and rigid fastening means so that the number of such elements are reduced without lessening the strength and rigidity of the car roof construction. And the invention comprehends such other objects and advantages of the invention as are found to obtain in the structure hereinafter described and claimed.

In the accompanying drawings, forming a part of this specification, and showing, for purposes of exemplification, a preferred form and manner in which the invention may be embodied and practiced, but without limiting the claimed invention specifically to such illustrative instance or instances:

Figure 1 is a top plan view of a portion of a car roof embodying the invention, portions of the same being broken away.

Fig. 2 is a longitudinal section taken at the ridge on the line 2—2 of Fig. 1, across one of the carlines.

Fig. 3 is a vertical cross section, taken at the eaves on the line 3—3 of Fig. 1.

Fig. 4 is a plan view of a portion of one of the carlines.

Fig. 5 is a side view of the same.

Fig. 6 is a transverse section of one of the carlines, taken on the line 6—6 of Fig. 4.

Fig. 7 is a vertical cross section of a portion of a car roof, taken on the line 7—7 of Fig. 1.

Fig. 8 is an enlarged detailed vertical cross section taken on the line 8—8 of Fig. 1, showing a manner of securing the roof sheets and carlines to the side plates.

Fig. 9 is a plan view of an intermediate roof sheet section.

Fig. 10 is a cross sectional view taken on the line 10—10 of Fig. 9.

Fig. 11 is a side view of such intermediate roof section.

Fig. 12 is a plan view of an end roof sheet section.

Fig. 13 is a cross sectional view taken on the line 13—13 of Fig. 12.

Fig. 14 is a side view of such end roof sheet section, showing the flange that is secured to an end member of the freight car.

Referring to the drawings, the upper part of the car body frame, which is the supporting frame for the roof, comprises side plates, which, in the present instance, are illustrated as of angle bar formation having a vertical web 10 extending longitudinally of the car, and an inclined transverse flange 11 extending outwardly from said web, but the invention is also intended for use with other types of side plates, the type of side plates illustrated being merely one of a plurality of well known conventional types of side plates.

Carlines 12 are spaced longitudinally of the car, and extend from side plate to side plate, spanning the open space therebetween. These carlines, in the present instance, are arched to conform to the pitch of the roof, and are formed to provide an upwardly projecting portion 13, of inverted channel cross section, having a rounded or curved top web 14, and outwardly flaring side webs 15 that terminate in oppositely disposed transversely and outwardly extending flanges 16. The upwardly projecting portion 13 is, and, consequently the top web 14 and side webs 15 are of constant dimensions from side plate to side plate, and the transverse outwardly extending flanges 16 are also of constant width from side plate to side plate, but over the top faces of the side plates, at each end, the top web 14 is inclined downwardly and outwardly to the outer extremities of the carline and such top webs 14 and side webs merge as is indicated at 17 thereby providing an end closure 17' for the inverted channel, and the transverse flanges are widened as

100
105

- shown at 18 and take up the excess metal resulting from the inclining of the top web and its merging with the side webs. The outer extremities 19 of the carlines, when positioned on the side plates, are secured within the outer edge 21 of the inclined flanges of the side plates, so that the carlines do not extend beyond the outside edges 21 of the side plates.
- 10 The intermediate roof sheet sections are also arched to conform to the pitch of the roof, and are comprised of a main body 22 extending clear across the car and terminating in vertical depending flanges 23 at the outside edges of the side plates. At each side edge, these intermediate roof sheet sections are offset upwardly a height sufficient to fit over the transverse flanges of the carline, so that the main body 22 of the sheet 15 may make contact with the top face of the side plates at the eaves as at 24, which contact together with the depending flanges 23 of such main body prevent entrance of water into the car.
- 15 These offset portions 25 extend clear across the car and are preferably of greater width than the width of the flanges 16 so as to clear the widened portions 18 of such flanges at the top face of the side-plates and also 20 to enable the roof sheet sections to be drawn tightly to the carlines so that they may be properly secured together, notwithstanding slight irregularities in the spacing of said carlines on said side plates, and such widening of said offset portions also helps to prevent buckling of the roof sheet sections.
- 20 These offset portions of the roof sheets terminate in carline engaging and enclosing flanges, and, in the present instance, one side flanging consists of an upwardly projecting portion 26 whose extremity is curved or rounded as at 27 to conform to and to engage the greater portion of the top web of the carline.
- 25 The offset portion of the opposite side edge of such roof section terminates somewhat similarly, except that it is formed to enclose the side flanging of its next adjacent sheet, and is provided with an upwardly projecting portion 28 which is bent at 29 to conform with the top web of the carline and thence extends down as at 31 over the opposite side web of the carline, so that it encloses substantially the entire upwardly projecting portion of the adjacent carline.
- 30 Each of the side webs of the carlines are perforated as shown at 32 to receive the shanks of rivets that, in the present instance, are used to secure the roof sheets tightly to the carlines. The end roof sheet sections are formed similarly to the intermediate roof sheet section, except that the edge that extends over the end plate of the car is not offset nor are flanges provided to engage a carline but instead the edge terminates in a
- 35 depending flange 33 which is rigidly fastened as by rivets 34 to an end member of the car.
- 40 The roof sheet sections are secured to the carlines so that the flange that consists of the upwardly projecting portion 26 and rounded portion 27, that engages only a greater portion of the top web of the carlines, is in contact with its adjacent carline and the flanging of the next adjacent roof sheet section encloses all of the upwardly projecting portion of the adjacent carline and also the flanging of the next adjacent sheet so that the side 28 of such flanging makes contact with the adjacent side web 29 of the adjacent carline and the top portion 29 and depending portion 31 makes contact with and encloses the side 26 and top 27 of said next adjacent roof sheet section flanging.
- 45 The roof sheet sections are secured rigidly to the car by rows of rivets 35 that pass through the side 28 of the flanging of one side of the roof sheet and the side web of the carline adjacent to said side 28. Another row of rivets 36 pass through the opposite side web of the carline and through the over-lapping edges 26 and 31 of adjacent roof sheets. These rivets 35 and 36 are arranged so that each rivet forms the apex of a triangle in a horizontal plane and so that each rivet is substantially midway between two rivets on the opposite side web of the carline, thereby lessening the number of rivets required without reducing the strength of the roof as a whole. At the 50 eaves ends, the roof sheets and carlines are riveted to the side plate by rivets 37 that pass through apertures 38 in the offset portions of the roof sheets and apertures 39 in the widened portions 18 of the carlines and through the top flange of the side plates.
- 55 The flanging of adjacent roof sheets at the eaves ends of the carlines are flattened and are lapped over the side plates as shown at 41 so that they are substantially in line with the depending eaves flanges 23 of the main body of the roof sheet sections, and as seen in Figs. 7 and 8.
- 60 A running board saddle and splice plate 42 is provided, having a horizontal portion 43 which supports the usual running boards 44 that are bolted to the portion 43 by bolts 45, and the saddle is also provided with a depending portion 46 which is secured to the over-lapped edges of the adjacent roof sheets at the ridge and to the adjacent side web of the carline, as shown in Fig. 2.
- 65 From the foregoing it will be noted that a substantial rigid all-steel roof construction is provided which is comparatively simple to assemble by reason of the rounded formation of the carlines and over-lapping roof sheet flanging which assembly is assisted by the offset portions enabling adjustment by reason of slight irregularities in spacing of the

carlines and it will also be observed that the roof may be rigidly constructed in water tight fashion with comparatively few rivets without reducing the rigidity and strength 5 of the roof construction as a whole.

The invention as hereinabove set forth is embodied in a particular form of construction but may be variously embodied within the scope of the claims hereinafter made.

10 I claim:

1. A car roof comprising, in combination: side plates each having a top flange; inverted channeled carlines spanning the open spaces between and secured to the upper portions of said side plates; said carlines each being arched to conform to the pitch of the roof and having an upper web and downwardly extending side webs, said side webs terminating in outwardly extending transverse flanges; metallic roof sheets arched in accordance with the pitch of the roof and extending from side plate to side plate, said roof sheets being offset at each side of the sheet from side plate to side plate, said offset portion being of greater width than said flanges, to fit over the transverse flanges of said carline and so that the main body of the sheet makes contact with the top flange of each of the side plates, 30 said offset portions terminating in carline engaging flanges, the flanges of adjacent roof sheets being lapped one over the other over said carlines; and means rigidly securing said roof sheets to said carlines.

2. In a car roof, in combination: a roof frame comprising side plates having an outwardly extending upper flange, and carlines, extending from side plate to side plate, of inverted channeled shape and provided with side webs, and with lateral flanges on their undersides, said carlines being secured to the upper flange of said side plates; roof sheets contacting with the upper flange of the side plates and having edge flanges bent to enclose said carlines, said roof sheet edge flanges being rigidly secured to said carlines by rivets passing through each side web of said carlines; the eaves ends of said edge flanges being flattened and extended down over the outer edges of said side plates together with the eaves edges of the main body of the roof sheet.

3. In a car roof, in combination: a roof frame comprising side plates, and carlines, extending from side plate to side plate, of inverted channeled shape and provided with side webs, and with lateral flanges on their undersides, said carlines being secured to the top faces of said side plates; roof sheets having edge flanges bent to enclose said carlines, said roof sheet edge flanges being rigidly secured to said carlines by rivets passing through each side web of said carlines; said rivets being arranged in said

edge flanges and carline side webs so that each rivet forms the apex of a triangle in a horizontal plane; the eaves ends of said edge flanges being flattened and extended down over the outer edges of said side plates together with the eaves edges of the main body of the roof sheet.

4. In a car roof, in combination: a roof frame comprising side plates, and carlines, extending from side plate to side plate, of inverted channeled shape and provided with side webs, and with lateral flanges on their undersides, said carlines being secured to the top faces of said side plates; roof sheets having edge flanges bent to enclose said carlines, said roof sheet edge flanges being rigidly secured to said carlines by rivets passing through each side web of said carlines; said rivets being arranged in said edge flanges and carline side webs so that each rivet is spaced a distance substantially midway between two rivets in the opposite side web of the carline; the eaves ends of said edge flanges being flattened and extended down over the outer edges of said side plates together with the eaves edges of the main body of the roof sheet.

5. A car roof comprising, in combination: side plates; inverted channeled carlines spanning the open spaces between and secured to the upper portions of said side plates; said carlines each being arched to conform to the pitch of the roof and having an upper web and downwardly extending side webs, said side webs terminating in outwardly extending transverse flanges; metallic roof sheets arched in accordance with the pitch of the roof and extending from side plate to side plate, said roof sheets being offset at each side of the sheet from side plate to side plate, said offset portion being of greater width than said flanges, to fit over the transverse flanges of said carline and so that the main body of the sheet makes contact with the side plates in a substantially horizontal plane, said offset portions terminating in carline engaging flanges, the flanges of adjacent roof sheets being lapped one over the other over said carlines; and means passing through each side web of the carlines for rigidly securing said roof sheets to said carline.

6. In a car roof, in combination: side plates, each of said side plates having at its upper edge an outwardly directed flange inclined downwardly; inverted channeled carlines having side webs secured to the outwardly directed flange of each of the side plates; roof sheets having edge flanges lapped over said carlines; and means passing through each side web of the carline for securing the roof sheets rigidly to said carlines.

7. In a car roof, in combination: side plates, each of said side plates having at

its upper edge an outwardly extending flange; inverted channeled carlines secured to the upper flange of said side plates; said carlines having a rounded upper web and side webs extending downwardly and inclined outwardly therefrom; roof sheets having edge flanges enclosing said carline, said edge flanges being shaped to conform with said carlines and rivets in each side web rigidly securing adjacent roof sheets to said carlines.

8. In a car roof, in combination: side plates; inverted channeled carlines secured to said side plates, said carlines consisting of a rounded upper web and two integral downwardly and outwardly sloping side webs terminating in transverse flanges, the eaves end portions of said top and side webs merging and providing a closed end for said channeled portion inclined from said top web to the ends of said carline; roof sheets having edge flanges enclosing said carline and secured thereto, the sheets being offset adjacent the said edge flanges and contacting with the side plates in only a substantially horizontal plane.

9. In a car roof, in combination: side plates; inverted channeled carlines secured to said side plates, said carlines having a rounded upper web and a plurality of side webs inclined downwardly and outwardly from said rounded top web, said side webs terminating in transverse flanges; roof sheets contacting with the side plates in only a substantially horizontal plane and having edge flanges for enclosing said carlines, one edge flange comprising a portion enclosing one side web and more than half of said top web, the other edge flange enclosing the edge flange of its adjacent sheet and the web of the carline adjacent its own sheet, the top web and the opposite side web of said carline; and rivets rigidly securing each of the webs of the carline to the flanges of roof sheets enclosing said webs.

10. In a car roof construction, the combination, with the two laterally spaced side plates each having an upper portion inclined outwardly and downwardly, and metal carlines spaced longitudinally and extending transversely of said side plates, each carline comprising an upwardly projecting portion which bridges the space between said carlines, said carline also comprising transversely and outwardly projecting flanges arranged at opposite sides of said

projecting portion, said carline being rigidly secured to the upper portions of said side plates by means passing through said transverse flanges; of sectional metal roofing comprising end sections and intermediate sections, said intermediate sections having one edge bent up over one side of the upwardly projecting portion of the carline adjacent said edge, and the other edge of said section being bent up over said carline to enclose said upwardly projecting portion and the edge of the next adjacent sheet that is bent up over one side of that carline and rivets rigidly securing to each side of the upwardly projecting portion of the carlines the edges of the sheets that are bent adjacent to each side of said upwardly projecting portion of the carline. 75

11. In a car roof construction, in combination: side plates, metallic carlines each comprising an upwardly projecting portion having a curved top web and flaring side webs, said carlines also having transverse outwardly projecting flanges arranged at opposite sides of said flaring webs, said carlines being rigidly secured to the top faces of said side plates by means passing through the portions of said carline transverse flanges that are arranged over the top faces of said side plates; of sectional metal roofing comprising end sections and intermediate sections, said intermediate sections having at each side an offset portion of greater width than the width of said transverse carline flanges, said offset portions terminating in upwardly projecting flanges formed to snugly fit the flaring side and top webs of said carlines, one of said upwardly projecting flange enclosing one side web and a portion of the top curved web of its adjacent carline and the other upwardly projecting flange enclosing the upwardly projecting flange of the roof section adjacent it and also both side flaring webs and the top curved web of its adjacent carline; and means rigidly securing the edges of said roof sections to the respective side flaring webs of the carline to which said edges are adjacent the eaves edges of the main body of said roof sections between said offset portions making contact with the side plates in a substantially horizontal plane and the outer edge portions of said sections being extended down over the outside edges of the side plates. 100 110

THOMAS NATHAN RUSSELL.
